(57) **CLAIM**

The ornamental design for a valve, as shown and described.

DESCRIPTION

FIG. 1 is a perspective view of a first embodiment of a valve including a transparent cap.

FIG. 2 is a right side view of the valve of FIG. 1.

FIG. 3 is a rear view of the valve of FIG. 1.

FIG. 4 is a top view of the valve of FIG. 1.

FIG. 5 is a front view of the valve of FIG. 1.

FIG. 6 is a bottom view of the valve of FIG. 1.

FIG. 7 is a left side view of the valve of FIG. 1.

FIG. 8 is a perspective view of a second embodiment of a valve similar to the embodiment in FIGS. 1-7, but includes an opaque cap.

FIG. 9 is a right side view of the valve of FIG. 8.

FIG. 10 is a rear view of the valve of FIG. 8.

FIG. 11 is a top view of the valve of FIG. 8.

FIG. 12 is a front view of the valve of FIG. 8.

FIG. 13 is a bottom view of the valve of FIG. 8; and,

FIG. 14 is a left side view of the valve of FIG. 8.

The broken line showing in FIGS. 1-5 and 7 is included for the purpose of illustrating portions of the valve and forms no part of the claimed design.
